CLAIM

The ornamental design for a sawing guide, as shown and described.

DESCRIPTION

FIG. 1 is a top plan view of a sawing guide showing my new design;

FIG. 2 is an enlarged view of FIG. 1 shown having the top portion broken away for ease of illustration thereof;

FIG. 3 is a perspective view of FIG. 1;

FIG. 4 is a bottom plan view thereof; and,

FIG. 5 is a side view, the opposite side being a mirror image thereof.

The broken line showing of numbers are for illustrative purposes only and form no part of the claimed design.

FIG. 1

FIG. 2

FIG. 3

FIG. 4

FIG. 5
